UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

AMMUNITION-HOISTING APPARATUS.

1,289,691.

Specification of Letters Patent. Patented Dec. 31, 1918.

Application filed May 15, 1915. Serial No. 28,491.

To all whom it may concern:

Be it known that we, Sir ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to Ammunition-Hoisting Apparatus, of which the following is a specification.

This invention relates to ammunition hoisting apparatus of the kind in which the projectile, after having been raised to the working chamber in a lower or hoist cage, is transferred to a transversely movable waiting tray from which, when the upper or gun loading cage descends into the working chamber and after the tray has been automatically moved to its discharging position, the projectile is rammed or otherwise moved on to the projectile tray of the gun loading cage.

According to the present invention the said projectile waiting tray, which is preferably pivotally mounted on the lower part of the powder charge waiting tray, is so constructed and arranged that when in the discharging position (with the hoist cage lowered) it lies vertically or approximately vertically above the hoist cage, the said projectile waiting tray being shifted laterally as the hoist cage rises so that it then occupies a receiving position to one side of the hoist cage. By these means we are able to economize space owing to the fact that the movements of the projectile waiting tray between the receiving and discharging positions take place within a space which is not greater than that circumscribed by the walls of the hoist trunk and it is therefore possible to arrange the said waiting tray within a vertical extension of the trunk. The saving of space renders the improved apparatus particularly applicable to a multiple turret. The means for automatically moving the waiting tray to and from its discharging position may comprise an operating cam moving with the ram of the hoisting press and preferably formed on the usual cut off cam of the press, the said operating cam being so arranged that the hoist cage approaches the working chamber, the waiting tray will

be moved to its receiving position while

when the cage descends the tray will be moved to its discharging position.

In order that the said invention may be clearly understood and readily carried into effect, we will describe the same more fully with reference to the accompanying drawings, in which:

Figures 1 and 2 are respectively a side elevation and an end elevation showing a constructional form of our improved hoisting apparatus, and Fig. 3 is a transverse section on a larger scale of the projectile receiver shown in Figs. 1 and 2.

A, A' are the hoist cages for the projectile and powder charges respectively, these cages being mounted on guide rails in the trunk B. C, C' are the projectile and powder charge waiting trays respectively. D is the hoisting press and D' the aforesaid operating cam moving with the ram of this press and formed on the cut off cam D².

In the example shown the projectile waiting tray C is pivotally mounted at c on the lower part of the powder charge waiting tray C' and is connected by suitable mechanism such as an arm c', links c², c³ and a rod c⁴ to one arm of a lever C² whose other arm carries a roller C³ engaging with the operating cam D'.

The drawings show in full lines the waiting tray C in the discharging position with the hoist cages A, A' at the lower end of the trunk B. When the ram of the hoisting press D moves downward in raising the hoist cages, the cam D' angularly displaces the lever C² in a clockwise direction and thereby moves the projectile waiting tray C into its receiving position indicated by chain lines in Fig. 2. This position is such that when the cage A reaches its uppermost position (also indicated by chain lines) the projectile can be caused by any suitable means to roll on to the tray C. During the descent of the cage the tray C is caused by the cam D' to resume its original position shown by full lines, in which position the projectile can be transferred by means of a rammer to the projectile tray of the gun loading cage which to avoid confusion is not shown in the drawings.

What we claim and desire to secure by Letters Patent of the United States is:

1. In ammunition hoisting apparatus, the combination with the projectile hoist cage, of a movable projectile waiting tray dis-

posed approximately vertically above the hoist cage when the latter is lowered, and means for moving said waiting tray so that it occupies a receiving position to one side 5 of the hoist cage when the latter is in its raised position.

2. In ammunition hoisting apparatus, the combination with the projectile hoist cage, of a movable projectile waiting tray disposed approximately vertically above the hoist cage when the latter is lowered, and means for moving said waiting tray so that it occupies a receiving position at the inner side of the hoist cage when the latter is in 15 its raised position.

3. In ammunition hoisting apparatus, the combination with the projectile hoist cage, of a movable projectile waiting tray disposed approximately vertically above the hoist cage when the latter is lowered, and means for automatically moving said waiting tray as the hoist cage is being raised so that said tray then occupies a receiving position to one side of the hoist cage when the latter is in its raised position.

4. In ammunition hoisting apparatus, the combination with the projectile hoist cage, of a movable projectile waiting tray disposed approximately vertically above the hoist cage when the latter is lowered, and means for automatically moving said waiting tray as the hoist cage is being raised so that said tray then occupies a receiving position at the inner side of the hoist cage when the latter is in its raised position.

5. In ammunition hoisting apparatus, the combination with the projectile hoist cage, of a movable projectile waiting tray disposed approximately vertically above the hoist cage when the latter is lowered, means for moving said waiting tray as the hoist cage is being raised so that said tray then occupies a receiving position at the inner side of the hoist cage when the latter is in its raised position, and means for displacing said waiting tray together with the projectile thereon to its first mentioned position as the cage descends.

6. In ammunition hoisting apparatus, the combination with the projectile hoist cage and the hoisting press thereof, of a laterally movable projectile waiting tray disposed approximately vertically above the hoist cage when the latter is lowered and a cam mov-

ing with the ram of said press for displacing said waiting tray to a receiving position at one side of the cage during the ascent of the latter and to its first mentioned position together with the projectile thereon during the descent of the cage.

7. In ammunition hoisting apparatus, the combination with the projectile hoist cage, of a pivoted projectile waiting tray disposed approximately vertically above the hoist cage when the latter is lowered, and means for rocking said waiting tray so that it occupies a receiving position to one side of the hoist cage when the latter is in its raised position.

8. In ammunition hoisting apparatus, the combination with the projectile hoist cage, of a powder charge waiting tray, a projectile waiting tray pivotally mounted on the lower part of said powder charge waiting tray and disposed approximately vertically above the hoist cage when the latter is lowered, and means for moving said projectile waiting tray so that it occupies a receiving position to one side of the hoist cage when the latter is in its raised position.

9. In ammunition hoisting apparatus, the combination with the projectile hoist cage and the trunk in which said cage is raised and lowered, of a movable projectile waiting tray disposed approximately vertically above the hoist cage when the latter is lowered, and means for moving said waiting tray so that it occupies a receiving position to one side of the hoist cage when the latter is in its raised position, said tray moving within a space which is not greater than that circumscribed by the walls of said trunk.

10. In ammunition hoisting apparatus, the combination with the projectile hoist cage and the trunk in which said cage is raised and lowered, of a vertical extension of said trunk, a laterally movable projectile waiting tray disposed within said extension in a position approximately vertically above the hoist cage when the latter is lowered, and means for moving said waiting tray so that it occupies a receiving position to one side of the hoist cage when the latter is in its raised position.

In testimony whereof we affix our signatures.

ARTHUR TREVOR DAWSON.
JAMES HORNE.
